A CORPORATION OF PENNSYLVANIA.

SHEET-FEEDING MECHANISM.

Application filed January 19, 1925. Serial No. 8,316.

Our invention relates to mechanisms for feeding in succession, sheets of material for any suitable purpose, and particularly for feeding sheets of paper or the like in a machine for applying adhesive to the sheets.

In accordance with our invention there is provided mechanism for feeding sheets in succession from a stack thereof, and particularly utilizable with sheets which do not lie flat but are deformed, as by curling or analogous effects, characterized by the provision of yielding or resilient holding means bearing upon the stack and the utilization of a suction roll with mechanism for controlling and operating the same, in such manner that the roll is applied to the stack at a substantial distance from an edge thereof and in moving from that position withdraws the sheet from the stack and delivers it to additional sheet feeding mechanism.

Further in accordance with our invention, the suction roll is associated with a tongue and feed roll, in combination with means for moving the tongue and feed roll as a unit with respect to the stack and to a fixed feed roll, and for moving the suction roll with respect to the stack in a path inclined with respect to the level of the stack, and with respect to the path of movement of the tongue and feed roll.

Further in accordance with our invention, the table or support for the stack is automatically elevated in response to decrease in number of sheets in the stack under the control of a member movable as a unit with the aforesaid tongue and feed roll and moved into engagement with the stack adjacent its edge or place of application of the suction roll in response to movement of said unit for effecting control of the mechanism which advances the table or support.

Structure of this character is utilizable, particularly in those cases where the sheets are of different thicknesses at or adjacent their edges and at or adjacent their centers, as in the case of embossed sheets. For this purpose, the stack engaging member, by virtue of its inclusion in the unit with the tongue and feed roll, engages the stack at or adjacent its edge, as distinguished from an area thereof more remote from the edge.

Our invention resides in mechanism of a character hereinafter described and claimed.

For illustration of one of the various forms our invention may take, reference is to be had to the accompanying drawings, in which:

Fig. 1 is a side elevational view, partly in vertical section on the line 1—1 of Fig. 2.

Fig. 2 is a top plan view, partly in section on the line 2—2 of Fig. 1.

Fig. 3 is a front elevational view, partly in section on the line 3—3 of Fig. 1.

Fig. 4 is a side elevational view, partly in section on the line 4—4 of Fig. 2.

Fig. 5 is a fragmentary horizontal section, partly in plan of the brush holder structure.

Referring to the drawings, there are supported upon the base or frame 1 channel shaped track members 2, in which roll in a rectilinear path the rolls 3 mounted upon stub shafts 4, mounted upon and supporting the carriage 5. Secured upon the rock shaft 6 are the levers 7 to whose upper ends there are pivoted at 8 the link structures 9, pivoted to the carriage 5 at 10, whereby the carriage 5 and the parts supported thereon are reciprocated forwardly and backwardly for each sheet fed.

Upon the vertically movable table or support 11, is disposed the stack S of sheets to be removed therefrom in succession. By mechanism hereinafter described, the table 11 is moved upwardly as the stack S diminishes in thickness in such wise as to cause engagement of the stack with the yielding or flexible members as bristle brushes 12, which serve to apply a resilient force upon the sheets at the front end of the stack to prevent the sheets from bowing or curling, or in general, to maintain the sheets in the stack sufficiently flat and thereby preventing feeding more than one sheet at a time. The brushes 12 are carried by the member or brush holder 13, adjustable toward and away from the stationary plate 14 carried by the frame 1 upon pins 15 carried by the member 14 and surrounded by helical springs 16 held in compression between the members 13 and 14. Adjustment of the brush holder 13 is effected by screws 17 threaded into the member 13 and engaging the plate 14.

Disposed upon the carriage 5 are upwardly and rearwardly extending arms 18 in which is pivoted the shaft 19 upon which are secured the forwardly extending arms

20 in which is pivoted the suction roll 21 provided at its opposite ends with rollers 22 rolling in the rectilinear channels 23 in the guide or track members 24 disposed in fixed position upon and with respect to the frame 1. Adjacent to its middle, the suction roll 21 is provided with a portion 25 of enlarged diameter having a cupped face 26, with which communicates the suction port 27 communicating with the bore 28 which is in continuous communication through the passage 29 with the stationary suction tube 30 and flexible tube 30^a connected, as hereinafter described, with a vacuum pump.

Extending transversely and secured to the carriage members 5 at opposite sides of the machine, is a bar 31 upon which are supported the bearings 32 for the idler feed rolls 33. Supported upon the bar 31 at 34 is the tongue or guide member 35 whose rear edge 36 is presented to the sheets as they are lifted by suction roll 21, and whose surface 37 guides the sheet to the feed roll 38.

Supported upon the frame 1 and positively driven, is the feed roll 38 between which and the feed roll 39, each sheet is clamped as it is withdrawn from the stack and fed by the rolls 33 and 38 to the feed rolls 39 and 40, driven and idling, respectively, which advance the sheet from the guide member 41 to the glue or adhesive distributing roll 42 and the co-acting guide roller 43. These rolls advance the sheet on to the conveyor belt 44 which passes over the roller 45, as well understood in the art.

The suction pipe 30 communicates through the valve chamber 46 with the suction pipe 47 communicating with the vacuum pump. A spring 48 normally holds the valve 49 against its seat, thereby sealing the chamber 46 against atmosphere. A bar 50, movable with the carriage 5, periodically engages and actuates the pivot member 51, causing it to thrust downwardly on the valve stem in opposition to spring 48, to open chamber 46 to atmosphere thereby discontinuing suction upon the suction roll 21.

Upon the bar 31 are carried the bearings 52 for the shaft 53 upon which is secured the arm 54 in whose outer end is threaded the screw 55 provided with collars 56 and 57 between which is disposed the outer end 58 of the arm 59 loosely pivoted upon the shaft 53 and extending rearwardly to form the feeler or stack-contacting member 60. Coiled about the shaft 53 is the spring 61, one end of which is secured to the bearing block 52 and whose other end is secured to the arm 62 secured to the shaft 53 and carrying at its outer end the plunger 63 which is adapted to engage the plate 14 upon rearward movement of the carriage 5. The spring 64 disposed within the arm 62 is compressed upon engagement of the member 63

with the plate 14 and returns the plunger 63 upon return forward movement of the carriage 5. Adjacent the side of the machine, there is secured upon shaft 53 the lever arm 65 which when rotating in counter-clockwise direction as viewed in Fig. 4, upon rearward movement of carriage 5 engages, under circumstances hereinafter to be described, and depresses the forward end of the lever 66, pivoted to the frame at 67. Pivoted to the lever 66 at 68 is the vertically movable plunger 69, upon which is carried the adjustable abutment 70 adapted to engage and depress the rod 71 to effect, as well understood in the art, actuation of the trip pawl 71^a to effect step-by-step rotation of the ratchet wheel 71^b by the dog 71^c oscillated through the rod 71^d by the rock shaft 6. The ratchet wheel 71^b effects the step-by-step rotation of the gear 72 secured upon the shaft 73 by means of which, through rack and pinion not shown, the table 11 is elevated a step at a time.

The operation is as follows:

The parts are indicated in Fig. 1 in their positions at the beginning of a cycle, the carriage 5 and parts carried thereby being at their extreme forward position. Shortly before the carriage 5 reaches its extreme forward position, member 50 has been withdrawn from the member 51, causing closure of the valve 49 and therefore exertion of suction upon the suction roller port 26 effecting suction of air therethrough. As the carriage 5 and therefore the suction roller 21 approaches the forward limit of its travel, the roller 21 is brought sufficiently close to the stack S to suck up the uppermost sheet and hold it to the enlarged portion 25 of the suction roller. Thereafter the carriage 5 moves rearwardly, drawing the sheet along, accompanied by an upward and rearward movement of the roller 21 as induced by movement of its rolls 22 in the upwardly and rearwardly inclined track channels 23, and simultaneously, the roller 21 is rotated in counter-clockwise direction, because of the rotation imparted thereto by the gear 74 secured to the roller 21 and meshing with the rack 75 extending upwardly and rearwardly parallel with the track channel 23. Accordingly the sheet held by suction to the roller 21 is wrapped partially around the roller, and withdrawn from beneath the brushes 12, in which position the forward (right) end of the sheet is directed upwardly toward the right, Fig. 1.

After predetermined extent of rearward movement of the carriage 5 and roller 21, the valve 49 is actuated, breaking the vacuum and releasing the sheet from the roller 21, whereupon the forward end of the sheet falls upon the guide surface 37 of the member 35. Continued rearward movement of the carriage 5 moves the tongue 35 with re-

lation to the sheet which is prevented from sliding backwardly by the back stop 76. This movement elevates the forward end of the sheet to such position that when the 5 roller 33 comes into contact with the driven feed roller 38, it is clamped between them and advanced upwardly toward the right by the counter-clockwise rotation of roller 38, and delivered between feed rolls 39 and 10 40 over the guide 41, between the rolls 42 and 43 and thence on to the conveyor belt 44 by which it is delivered to the box wrapping machine or any other destination. The rearward stroke of the carriage 5 is now 15 completed and it therefore returns to its forward position indicated and immediately before completion of its forward movement a new cycle of operations is begun for feeding the next succeeding sheet.

20 In the operations described, the brushes 12 insure that a single sheet only will be picked up by suction roll 21 and delivered to the succeeding feeding elements.

The inclination of the path of movement 25 on the suction roll is desirable and effective because of the presence of the brushes 12, and because further, the recession of the suction roller from the stack is desirable or necessary in those cases where the sheets 30 consist of soft material or are thicker at their central areas than at their edges, as in the case of embossed sheets.

The rock shaft 6, Fig. 4 imparts successive 35 rotary movements to the shaft 73 causing successive small upward movements of the table or support 11 so long as the lever 66 is depressed, which occurs when upon rearward and downward movement of the feeler member 60, there is not imparted thereby 40 through the member 62 and shaft 53 suitable great downward movement of the member 65. Accordingly as the height of the stack S decreases as the result of withdrawal of the successive sheets therefrom the member 45 60 is deflected sufficiently to cause deflection of the lever 66, and thereby cause resumption of upward feed of the table 11.

Upon exhaustion of the stack S, when no 50 sheets remain upon the table 11, the feeler member 60 engages the table 11, thereby preventing sufficient angular movement of the member 60 to prevent depression of the member 66, and so discontinuing and preventing further upward feed of the table 11.

55 Inasmuch as it is desirable to effect control of the upward feed of the table 11 from that portion of the upper face of the stack S at which the suction is applied for picking up sheets, the table feed control member 60 is 60 mounted upon the carriage 5 or moves as a unit with the tongue 35 and feed roll 33, in order that the table feed shall depend upon changes in height of stack adjacent the edge thereof particularly in case of sheets of 65 greater or different thickness at their mid-

dles as compared with the thickness at their edges, as in the case of embossed box wrappers, or as in the case of sheets of soft material.

It is further desirable to mount the table 70 control member 60 upon the carriage due to the fact that it is essential that the member 60 be removed from the path of the sheet next to be picked up. That is to say, the member 60 must be moved forward to operative position with respect to the stack, and withdrawn therefrom between the withdrawals from the stack of successive sheets.

What we claim is:

1. Apparatus for feeding sheets from a 80 stack thereof comprising means engaging the top of the stack adjacent an edge thereof, suction means for picking a sheet from the top of the stack, and means for imparting movement to said suction means in a 85 path inclined with respect to the top of the stack for withdrawing the sheet therefrom.

2. Apparatus for feeding sheets from a 90 stack thereof comprising means engaging the top of the stack adjacent an edge thereof, suction means for picking a sheet from the top of the stack, and means for imparting to 95 said suction means a motion of rotation and a motion of translation in a path inclined to the top of the stack for withdrawing the sheet from the stack.

3. Apparatus for feeding sheets from a 100 stack thereof comprising means yieldingly engaging the top of the stack adjacent an edge thereof, suction means for picking a 105 sheet from the top of the stack, and means for imparting to said suction means a motion of rotation and a motion of translation in a path inclined to the top of the stack for withdrawing the sheet therefrom.

4. Apparatus for feeding sheets from a 110 stack thereof comprising brush structure engaging the top of the stack adjacent an edge thereof, suction means for picking a sheet from the top of the stack, and means for imparting to said suction means a motion of rotation and a motion of translation in a path 115 inclined to the top of the stack for withdrawing the sheet therefrom.

5. Apparatus for feeding sheets from a 120 stack thereof comprising means engaging the top of the stack adjacent an edge thereof, a holder for said stack-engaging means, a fixed member, means for adjusting said holder with respect to said fixed member to effect 125 adjustment of the extent of projection of said stack-engaging means over the edge of the stack, suction means for picking a sheet from the top of the stack, and means for imparting movement to said suction means to withdraw the sheet from said stack-engaging means.

6. Apparatus for feeding sheets from a 130 stack thereof comprising means engaging the top of the stack adjacent an edge there-

- of, a holder for said stack-engaging means, a fixed member, means for adjusting said holder with respect to said fixed member to effect adjustment of the extent of projection of said stack-engaging means over the edge of the stack, suction means for picking a sheet from the top of the stack, means for imparting movement to said suction means to withdraw the sheet from said stack-engaging means.
10. Apparatus for feeding sheets from a stack upwardly toward said stack-engaging means.

7. Apparatus for feeding sheets from a stack thereof comprising a carriage movable backwardly and forwardly with respect to the stack, and a suction roll movable with said carriage and movable in a path at an angle to the path of movement of said carriage.

8. Apparatus for feeding sheets from a stack thereof comprising a carriage movable backwardly and forwardly in a path substantially parallel with the upper face of the stack, and a suction roll movable with said carriage and with respect to said carriage in a path inclined with respect to the upper face of the stack.

9. Apparatus for feeding sheets from a stack thereof comprising a carriage movable backwardly and forwardly with respect to the stack, a suction roll movable with said carriage and movable in a path at an angle to the path of movement of said carriage, and means for rotating said roll while moving in said path.

10. Apparatus for feeding sheets from a stack thereof comprising a carriage movable backwardly and forwardly in a path substantially parallel with the upper face of the stack, a suction roll movable with said carriage and with respect to said carriage in a path inclined with respect to the upper face of the stack, and means for rotating said roll while moving in said path.

11. Apparatus for feeding sheets from a stack comprising a member for picking a sheet from the stack movable in a direction having components parallel and at right angles to a face of the stack, and a guide member for the sheet movable with respect to the stack and with respect to which said member is movable.

12. Apparatus for feeding sheets from a stack comprising a member for picking a sheet from the stack movable in a direction having components parallel and at right angles to a face of the stack, a guide member for the sheet movable with respect to the stack, and a feed roll movable with said guide member.

13. Apparatus for feeding sheets from a stack thereof comprising a suction roll movable in a direction having components parallel and at right angles to a face of the stack, and a guide member for the sheet mov-

able with respect to the stack and with respect to which said roll is movable.

14. Apparatus for feeding sheets from a stack thereof comprising a suction roll movable in a direction having components parallel and at right angles to a face of the stack, a guide member for the sheet movable with respect to the stack, and a feed roll movable with said guide member.

15. Apparatus for feeding sheets from a stack thereof comprising a suction roll movable in a direction having components parallel and at right angles to a face of the stack, a guide member movable with respect to the stack, and with respect to which said roll is movable, and means for rotating said suction roll.

16. Apparatus for feeding sheets from a stack thereof comprising a suction roll movable in a direction having components parallel and at right angles to a face of the stack, a guide member for the sheet movable with respect to the stack, a feed roll movable with said guide member, and means for rotating said suction roll.

17. Apparatus for feeding sheets from a stack thereof comprising a carriage movable backwardly and forwardly with respect to the stack, a member mounted on said carriage for picking a sheet from the stack, means for imparting to said member movement in a direction at an angle to the direction of movement of said carriage, and a co-acting guide member on said carriage.

18. Apparatus for feeding sheets from a stack thereof comprising a carriage movable backwardly and forwardly with respect to the stack, a member mounted on said carriage for picking a sheet from the stack, means for imparting to said member movement in a direction at an angle to the direction of movement of said carriage, a co-acting guide member on said carriage, and a feed roll on said carriage.

19. Apparatus for feeding sheets from a stack thereof comprising a carriage movable backwardly and forwardly with respect to the stack, a suction roll on said carriage and movable in a direction at an angle to the direction of movement of said carriage, means for rotating said roll, and a co-acting guide member on said carriage.

20. Apparatus for feeding sheets from a stack thereof comprising a carriage movable backwardly and forwardly with respect to the stack, a suction roll on said carriage, and a fixed member enforcing movement of said roll with respect to said carriage in a direction at an angle to the direction of movement of said carriage.

21. Apparatus for feeding sheets from a stack thereof comprising a carriage movable backwardly and forwardly with respect to the stack, a suction roll on said carriage, a fixed member enforcing movement of said

- 5 22. Apparatus for feeding sheets from a stack thereof comprising a carriage movable backwardly and forwardly with respect to the stack, a suction roll on said carriage, a fixed member enforcing movement of said 70 roll with respect to said carriage in a direction at an angle to the direction of movement of said carriage, and a guide member co-acting with said roll and movable with said carriage.
- 10 23. Apparatus for feeding sheets from a stack thereof comprising a carriage movable backwardly and forwardly with respect to the stack, a suction roll on said carriage, a fixed member enforcing movement of said 80 carriage.
- 15 24. Apparatus for feeding sheets from a stack thereof comprising a carriage movable backwardly and forwardly in a path substantially parallel with a face of the stack, a member pivoted on said carriage, a 85 90 95 roll with respect to said carriage in a direction at an angle to the direction of movement of said carriage, means for rotating said roll, and a guide member co-acting with said roll and movable with said carriage.
- 20 25. Apparatus for feeding sheets from a stack thereof comprising a carriage movable backwardly and forwardly in a path substantially parallel with a face of the stack, a member pivoted on said carriage, a 100 105 110 115 120 125 130 suction roll carried by said member, and means causing pivotal movement of said member with respect to said carriage to effect movement of said roll with respect to said carriage in a path at an angle to the path of movement of said carriage.
- 25 26. Apparatus for feeding sheets from a stack thereof comprising a carriage movable backwardly and forwardly in a path substantially parallel with a face of the stack, a member pivoted on said carriage, a suction roll carried by said member, means causing pivotal movement of said member with respect to said carriage to effect movement of said roll with respect to said carriage in a path at an angle to the path of movement of said carriage, and means for rotating said roll.
- 30 27. Apparatus for feeding sheets from a stack thereof comprising a carriage movable backwardly and forwardly in a path substantially parallel with a face of the stack, a member pivoted on said carriage, a suction roll carried by said member, means causing pivotal movement of said member with respect to said carriage to effect movement of said roll with respect to said carriage in a path at an angle to the path of movement of said carriage, means for rotating said roll, and a guide member co-acting with said roll mounted on said carriage.
- 35 28. Apparatus for feeding sheets from a stack thereof comprising sheet-picking means, feeding mechanism for effecting approach toward each other of said means and stack, and means controlling said feeding mechanism comprising a member movable toward and away from the stack along a path substantially parallel with the top of the stack and into engagement with the stack.
- 40 29. Apparatus for feeding sheets from a stack thereof comprising sheet-picking means, feeding mechanism for effecting approach toward each other of said means and stack, and means controlling said feeding mechanism comprising a member, means for imparting to said member a motion of translation toward and away from the stack, and means for imparting to said member a motion of rotation into engagement with the stack.
- 45 30. Apparatus for feeding sheets from a stack thereof comprising sheet-picking means, feeding mechanism for effecting approach toward each other of said means and stack, and means controlling said feeding mechanism comprising a member, means for imparting to said member a motion of translation toward and away from the stack, means for imparting to said member a motion of rotation into engagement with the stack, and means operative in response to predetermined extent of said motion of rotation to effect control of said feeding mechanism.
- 50 31. Apparatus for feeding sheets from a stack thereof comprising sheet-picking means, feeding mechanism for effecting approach toward each other of said means and stack, a carriage movable toward and away from said stack, and means controlling said feeding mechanism comprising a member pivoted on said carriage and adapted to engage the stack.
- 55 32. Apparatus for feeding sheets from a stack thereof comprising sheet-picking means, feeding mechanism for effecting approach toward each other of said means and stack, a carriage movable toward and away from said stack, and means controlling said feeding mechanism comprising a member pivoted on said carriage, and means for rotating said member into engagement with the stack comprising an abutment, and a member movable with said carriage into engagement with said abutment.

33. Apparatus for feeding sheets from a stack thereof comprising a movable carriage, a suction roll on said carriage for picking a sheet from the top of the stack, mechanism 5 for feeding the stack upwardly toward said roll, and means for controlling said feeding mechanism comprising a member pivoted on said carriage, means for deflecting said member toward the stack adjacent the edge 10 thereof in response to movement of said carriage toward the stack, and means effecting control of said feeding mechanism controlled by said pivoted member.
34. Apparatus for feeding sheets from a stack thereof comprising a carriage movable toward and away from the stack, a suction roll on said carriage, means for imparting to said roll movement in a direction at an angle with respect to the direction 15 of movement of said carriage, said roll adapted to co-operate with the stack adjacent an edge thereof for picking a sheet therefrom, a co-acting guide member movable with said carriage, mechanism for feed- 20
- ing the stack toward said suction roll, and 25 means for controlling said feeding mechanism comprising a member pivoted upon said carriage and movable thereby to a position over the stack adjacent said edge, means responsive to movement of said carriage for 30 deflecting said pivoted member toward the face of the stack, and means responsive to predetermined pivotal movement of said member effecting control of said feeding mechanism. 35
35. Apparatus for feeding sheets from a stack thereof comprising means engaging the top of the stack adjacent an edge thereof, suction means adapted to engage the top sheet of said stack adjacent said edge, and 40 means for imparting movement to said suction means to and away from said edge along a path inclined with respect to the top of the stack for withdrawing said sheet from engagement by said first means.

CHARLES H. NITSCH.
JOSEPH W. BAKER.
